CLAIM

The ornamental design for a leaf patterned light bulb, as shown and described.

DESCRIPTION

FIG. 1 is a perspective top view of a leaf patterned light bulb showing our new design.

FIG. 2 is a perspective bottom view of the leaf patterned light bulb.

FIG. 3 is a top plan view of the leaf patterned light bulb.

FIG. 4 is a bottom plan view of the leaf patterned light bulb.

FIG. 5 is a side elevational view of the leaf patterned light bulb.

FIG. 6 is a side, cross-sectional view of the leaf patterned light bulb taken from the line 6-6 in FIG. 5.

FIG. 7 is a side view of a minimally modified variation of the leaf patterned light bulb of FIG. 1.

FIG. 8 is a side view of a minimally modified variation of the leaf patterned light bulb of FIG. 1.

FIG. 9 is a side view of a minimally modified variation of the leaf patterned light bulb of FIG. 1.

FIG. 10 is a side view of a minimally modified variation of the leaf patterned light bulb of FIG. 1; and,

FIG. 11 is a side view of a minimally modified variation of the leaf patterned light bulb of FIG. 1.

The broken lines in the drawings depict parts of the leaf patterned light bulb that form no part of the claimed design.
